W. N. DALY.

COMBINATION FRONT AND REAR LIGHT, NUMBER PLATE, AND PLATE HOLDER.
FILED DEC. 13, 1920.

William N. Daly Inventor:
by Charles W. Corlett,
Attorney.

UNITED STATES PATENT OFFICE.

WILLIAM N. DALY, OF MIDDLETON, MASSACHUSETTS.

COMBINATION FRONT AND REAR LIGHT, NUMBER PLATE, AND PLATE HOLDER.

Application filed December 13, 1920. Serial No. 430,145.

To all whom it may concern:

Be it known that I, WILLIAM N. DALY, citizen of the United States, residing at Middleton, in the county of Essex and State 5 of Massachusetts, have invented certain new and useful Improvements in a Combination Front and Rear Light, Number Plate, and Plate Holder, of which the following is a specification.

10 My invention relates to a combination front or rear light, number plate and plate holder, box like in shape, for use on automobiles or other vehicles, in which a stenciled plate is held in position within a holding box-frame, and the stenciled letters and figures of the plate illuminated by means 15 back of the same.

The objects of my invention are: to provide an illuminated number plate easily discernible by day or night,

20 To provide an improved number plate holder,

To provide a combination rear light and number plate, or an illuminated front number, and to secure other advantages and results some of which are hereinafter referred to.

I accomplish the objects of my invention as illustrated in the accompanying drawing 30 in which—

Figure 1, shows a front view of my plate holder, with one half of the cover removed therefrom.

Figure 2, shows the stenciled number plate 35 used in my improved holder, and also shows the outline of a red transparent plate which lies beneath and parallel therewith.

Figure 3, shows a sectional view on the line A—A in Figure 1.

40 Figure 4 shows an end view of my device.

Similar letters refer to similar parts throughout the several views.

In Figure 1, B, shows the rear of my box-shaped plate holder. C, shows the sides of the same. The location of the cover D, is shown by the dotted lines. E, shows the hinges which secure the cover D, to the box frame. F, shows the cleats by means of 45 which my device is secured to the vehicle on which it is to be used. G, shows the holding nuts by means of which the exteriorly threaded socket H, is secured to my box holder. I, shows the electric bulb which 50 furnishes the required illumination by night. The center portion of the rear side of my

box-holder is of glass, X, or other transparent substance, the center, Y, of the cover side of my box holder is also of glass or other transparent substance. 60

In Figure 2, J, shows the location of the figure shaped stencil openings in the opaque number plate, K. J' shows the circular stencil opening which forms the red light. A red transparent plate K', is provided, of 65 the same size as the stenciled plate and is assembled directly beneath the same so as to show red through the stencil openings, J and J'.

In Figure 3, the dotted lines D, show the 70 position of the cover portion when opened to receive the stenciled number plate. H', shows the lower portion of the socket which extends below the box holding device. Z, shows the angle brackets which support and 75 hold the plates K and K' against the cover D.

In Figure 4, L, shows the holding bolts with which the cover portion, D, of the box holding device is fastened down in use. L', shows the nut which secures the holding 80 bolt in position.

In operation illumination is provided at night by means of the electric bulb, I, the rays from which penetrate the red transparent plate K', the stencil openings, J, and 85 J', and the clear section Y of the cover D. By day illumination is not required, but is furnished to some extent by the opening, X, in the rear side of the box holding device and causes the red color of the transparent 90 plate, K', to show clearly through the stencil openings in the number plate K. It will be understood that when my device is used as a front number plate and holder the circular stenciled opening J' is not essential 95 and that the transparent plate K' will be white rather than red.

It will also be understood that stencil plates of various sizes can be used and that my device is as adaptable for motor cycles 100 as for other uses.

Having thus described my invention I claim as new and desire to secure by Letters Patent of the United States.

1. A device of the character described 105 comprising a lamp casing having an opening in the back, a cover hinged to the said casing and being likewise provided with an opening, a transparent plate arranged over each opening, means carried by the casing 110 and coacting with the hinged cover to provide plate-holding means at the front of the

casing, a number-plate between the casing and the cover, said plate being clamped to the casing by the closing of the cover and released for removal by the opening of the 5 cover, and illuminating means within the casing rearwardly of the said plate.

2. A device of the character described comprising a casing having an opening in the back, a cover hinged to the casing and 10 being likewise provided with an opening, a transparent plate arranged over each opening, angle brackets extending inwardly from adjacent the outer or cover edge of the casing, a transparent plate disposed to lie 15 against the said brackets, a stenciled plate disposed over the outer face of the transparent plate, said stencil plate and said last mentioned transparent plate being clamped firmly between the said brackets and the 20 said cover by the closing of the latter and being removable upon the opening of the cover, and lamp means within the casing.

3. A device of the character described comprising a casing having an opening in the back, a hinged cover carried by the casing and being likewise provided with an 25 opening, a transparent plate arranged over each opening, brackets depending from the casing on the inside thereof and in slightly 30 spaced relation to the front edges of the casing, a pair of laterally disposed plates arranged within the front edge of the cas-

ing and supported by the said brackets, the outermost of said plates being stenciled and the innermost plate providing a transparent 35 backing for the stenciled outer plate, said plates being clamped firmly against the said brackets by the pressure of the door when the latter is closed and being removable by the opening of the cover, and means for 40 locking the cover to the casing.

4. A device of the character described comprising a casing having an opening in the back, a cover hinged to the said casing and being likewise provided with an opening, a transparent plate arranged over each 45 opening, brackets depending inwardly of the cover adjacent the front edge thereof, a stenciled number-plate disposed within the front edge of the casing and supported 50 by the said brackets, said plate being clamped against the said brackets by the pressure of the door when the latter is closed and being removable from the casing upon 55 opening the cover, and means for locking the cover to the casing, said means being adjustable for varying the pressure of the said cover on the said plate.

In testimony whereof I affix my signature in the presence of two witnesses.

WILLIAM N. DALY.
